(57) **CLAIM**

The ornamental design for a pool cleaning device, as shown and described.

DESCRIPTION

FIG. 1 is a perspective angled front view of the pool cleaning device, which embodies my design;

FIG. 2 is a front view thereof;

FIG. 3 is a rear view thereof;

FIG. 4 is an enlarged top view thereof;

FIG. 5 is an enlarged bottom view thereof;

FIG. 6 is an enlarged left side view thereof;

FIG. 7 is an enlarged right side view thereof;

FIG. 8 is a perspective view thereof being partially wrapped about a pool brush head; and,

FIG. 9 is a perspective view thereof being wrapped around a pool brush head.
Portions of the drawings shown in short dashed broken lines represent stitching. Portions of the brush head in FIGS. 8 and 9 shown in long dashed broken lines form no part of the claimed design.
